UNITED STATES PATENT OFFICE.

WILLIAM F. HENDRY, OF OSSINING, NEW YORK, ASSIGNOR TO MANHATTAN ELECTRICAL SUPPLY COMPANY, INC., A CORPORATION OF MASSACHUSETTS.

ADVERTISING SIGN SYSTEM.

Application filed October 2, 1926. Serial No. 139,223.

This invention relates to new and useful improvements in systems for advertising signs and particularly to one adapted for use with luminous tube signs.

5 The present invention provides for the ready installation and removal of the luminous tubes making up the sign; means for the proper spacing of such tubes; protection of electrical parts against water, dust, etc.; suitable mounting for electrical circuit controllers; and other features the nature of which will more clearly appear from the following detailed description of a preferred embodiment of the invention and the 10 appended claims.

In the drawings Fig. 1 is a perspective view (with parts broken away) of a complete sign display; Fig. 2 schematically illustrates the circuit connections; and Fig. 20 3 is a perspective view showing the mounting of a circuit controller.

Neon filled luminous letters such as 1 are mounted in a metal housing open at the front and having a top 2, a back 3 and a 25 bottom 4. The top 2 has a bent down edge 5 which with an angle piece 6 fastened to the top 2 constitutes a slide for templates such as 7. Slightly to the rear, another slide 8 is fastened to the top 2 for diaphragms such as 9. These two slides run to the full width of the housing where it is desired to mount letters 1. The diaphragm plates 9 are bent at right angles at the bottom into a toe 10 which slides between flat 30 35 steel strips 11 and 12 which, together with an L-shaped steel strip 13, are held against the edge of the bottom plate 4 of the housing by means of screws such as 14. By tightening the screws 14, the diaphragms 40 may be securely held in place against all displacements.

The lateral edges of each diaphragm 9 are provided with marginal folds 17 and 18 which are bent, (in opposite directions) at a 45 slight angle with respect to the plane of the diaphragm. When a diaphragm 9 is pushed into the slide 8, its fold 18 will glide under the fold 17 of the adjacent diaphragm. In this manner the center lines of 50 adjacent diaphragms may be displaced with respect to each other as may be necessary for the proper spacing of adjacent letters.

The lower edge of each template 7 overhangs the vertical leg of the L-shaped strip 55 13 and is held in place by a clamping strip

15 secured by screws 16. By removing a clamping strip 15, the template 7 may be removed from the housing.

Each diaphragm 9 has a central perforation through which a bolt or rod 19 projects by means of which a socket 20 of porcelain or other insulating material may be held against the diaphragm. The socket has two large openings 21 and 22 which are in alignment with openings 23 and 24 in 60 the diaphragm. The bolt 19 projects through the socket and carries at its protruding end a coiled spring 25 which may be placed under tension by a nut 26 to press the socket against the diaphragm. However, the face of the socket 20 is spaced by means of projections 27 whereby water, dust, etc., will fall down between diaphragm and socket instead of entering the openings 21 and 22. 70 75

A suitably bent spring 28, 29 projects into each opening and serves to make contact with and frictionally to hold in place the electrodes 30, 31 of a letter 1. The rear ends 32, 33 of these springs, projecting 80 through openings 21, 22 are bent at right angles and are fastened to bosses (only one is shown) 34 of the socket 20. Springs 32 and 33 contact, respectively, with bus bars 35 and 36 which are supported on the back 85 plate 3 by angles such as 37 of insulating material. If the alignment of the letters is not as desired, the socket of any letter may be turned around bolt 19 to the right or left. A bend 38 in the ends of springs 32 and 33 90 will keep them from being moved out of contact with the bus bars.

The templates 7 are cut out to display the letters 1. The ends of the housing are closed by caps 39. 95

The circuit arrangement of the sign is shown in Fig. 2. All the sockets 20 are connected by means of their springs 32 and 33 in parallel across the bus bars 35 and 36. The bar 35 is connected through a conductor 40 with a spring 41 which contacts with a terminal 42 of the secondary winding 43 of an induction coil. The other bar 36 is connected through conductors 46 and 47 with a spring 44 which contacts with the 100 other terminal 45 of secondary 43. One end of the primary winding 48 is connected with the secondary 43, and the other end with a back contact 49 engaging an armature 50 which may be vibrated by the magnetic core 105 110

51 of the induction coil. The armature is connected with a terminal 52 provided on a box 53 enclosing the induction coil.

A spring 54 contacting with terminal 52 is connected through conductor 55 with one terminal of the secondary winding of a transformer 56, the other terminal of said secondary being connected with conductor 46. If the transformer primary is connected 10 with an alternating current source of 110 volts, the bus bars 35, 36 will be supplied with high frequency current through the agency of the induction coil which opens and closes its primary circuit 48 at the 15 interrupter 49, 50, and the letters will be rendered luminous.

The induction coil is mounted within the housing near the end cap 39. By means of partitions 57 and 58 a compartment is 20 formed within which the box 53 may be placed so that its terminals 42, 45 and 52 will contact with the springs 41, 44 and 54. The springs 41 and 44 are mounted on partition 57 properly insulated therefrom, and 25 the spring 54 is mounted on partition 58 insulated by block 59. The transformer 56 is mounted on the bottom 4 of the housing.

The transformer primary may be connected with the alternating current source 30 through a cord 60 passing through an opening in the bottom wall 4 of the housing. At this end, the housing is enclosed by a front wall 61.

The complete sign may be sent to the user 35 readily assembled for connection with an electric light socket. The sign letters may be changed by removing a few screws, and the coil box is at all times accessible by removing the end cap 39.

40 By virtue of the slidable diaphragms the sign letters may be spaced a proper distance apart and by means of the rotatable mounting of the sockets the letters can be properly positioned in relation to the templates which 45 outline the letters.

What I claim is:

1. In a housing for luminous sign letters, 50 a socket for each letter, a plate for each socket, a shaft on said plate rotatably supporting the socket, means for mounting said plates to permit displacement in overlapping relation to each other, contact springs in said sockets, and bus bars contacting with said contact springs in all positions of said plates and sockets.

2. In a support for luminous sign letters, 55 a socket for each letter, a guiding member, a plate for each letter slidably mounted on said guiding member, and means for rotatably mounting each of said sockets on said plate.

3. In a housing for luminous sign letters, 60 a socket for each letter, means for mounting said sockets to permit lateral and rotary displacement of said sockets, contact springs in

said sockets, and stationary bus bars engaged by said contacts in all positions of said sockets.

4. In a mounting for luminous signs of the two-electrode type, a socket within which the electrodes may be placed, contact springs within said socket for resiliently holding in place said electrodes, and means for rotatably supporting said socket on said mounting. 70

5. In a mounting for luminous signs of the two-electrode type, a socket having two large openings within which the electrodes may be placed and a central perforation between said openings, contact springs within 75 said openings for resiliently holding in place said electrodes, a plate having openings corresponding to those in said socket, projections on the face of said socket, a rod projecting through said plate and said central perforation in said socket, resilient means pressing the face of said socket against said plate, a stationary bus bar above and below said socket, and an extension for each of said contact springs frictionally engaging said 80 bus bars.

6. In a mounting for luminous signs of the two-electrode type, a socket having two large openings within which the electrodes may be placed and a central perforation between said openings, contact springs within 85 said openings for resiliently holding in place said electrodes, a plate having openings corresponding to those in said socket, projections on the face of said socket, a bolt projecting through said plate and said central perforation in said socket, a coiled spring on said bolt pressing the face of said socket against said plate, a stationary bus bar above and below said socket, and an extension for each of said contact springs frictionally engaging said bus bars, the ends of 90 said extensions being bent at substantially right angles to overhang the adjacent bus bar. 100

7. In a mounting for luminous signs of the two-electrode type, a housing open at the front, two bus bars mounted in said housing on the rear wall thereof, a plurality of diaphragms having two openings for the passage of electrodes and oppositely bent lateral folds, a slide in the top of the housing with which the top edge of each diaphragm cooperates, clamping means in the bottom of said housing cooperating with the lower edges of said diaphragms, a socket for each sign, a bolt projecting through said diaphragm and said socket, a coiled spring on said bolt pressing said socket against said diaphragm, spacers between said socket and diaphragm, contact springs mounted on said socket and frictionally engaging said bus bars, a casing comprising a circuit interrupter and induction coil, a compartment in 115 said housing for said casing, contacts of said 120 bus bars, and a cover for said compartment. 125

bus bars projecting within said compartment, a transformer in said housing, and a connection to said transformer projecting within said compartment.

- 5 8. In a mounting for luminous signs of the two-electrode type, a housing open at the front, two bus bars mounted in said housing on the rear wall thereof, a plurality of diaphragms having two openings for the 10 passage of electrodes and oppositely bent lateral folds, a slide in the top of the housing with which the top edge of each diaphragm cooperates, clamping means in the bottom of said housing cooperating with the 15 lower edges of said diaphragms, a socket for each sign, a bolt projecting through said diaphragm and the socket, a coiled spring on said bolt pressing said socket against said diaphragm, spacers between said socket and 20 diaphragm, contact springs mounted on said socket and frictionally engaging said bus bars, a plurality of templates cut out to display said signs, means for removably attaching said templates to the front of said housing, a casing comprising a circuit interrupter and induction coil, a compartment in said housing for said casing, contacts of said bus bars projecting within said compartment, a transformer in said housing, and a connection to said transformer projecting within said compartment. 50
9. In a mounting for luminous signs of the two-electrode type, a housing open at the front, two bus bars mounted in said housing on the rear wall thereof, a plurality of 25

diaphragms having two openings for the passage of electrodes and oppositely bent lateral folds, a slide in the top of the housing with which the top edge of each diaphragm cooperates, clamping means in the bottom of said housing cooperating with the lower edges of said diaphragms, a socket for each sign, a bolt projecting through said diaphragm and the socket, a coiled spring on said bolt pressing said socket against said diaphragm, spacers between said socket and diaphragm, contact springs mounted on said socket and frictionally engaging said bus bars, a plurality of templates cut out to display said signs, means for removably attaching said templates to the front of said housing, a casing comprising a circuit interrupter and induction coil, a compartment in said housing for said casing, contacts of said bus bars projecting within said compartment, a transformer in said housing, and a connection to said transformer projecting within said compartment. 45

In testimony whereof, I have signed my name to this specification this 1st day of October, 1926.

WILLIAM F. HENDRY.
